UNITED STATES PATENT OFFICE.

WILLIAM V. LIPPERT, OF CHICAGO, ILLINOIS, ASSIGNOR TO THE NORLIPP COMPANY, OF CHICAGO, ILLINOIS, A CORPORATION OF ILLINOIS.

RADIATOR-LOCKING CAP.

Application filed February 19, 1923. Serial No. 619,819.

My invention relates to automobile radiator caps of the general type of that shown and described in my pending application, Serial No. 540,990.

5 A primary object of the present invention is the provision of an improvement whereby the parts of the device may be more readily assembled than has proved to be possible with the construction of my prior application, thus rendering more practicable the supply of the parts to jobbers or dealers in separate units, one of which may be of standard construction, not requiring change to suit different types of cars. In this connection, it is contemplated that an insert, or 10 internal unit, may be supplied, independently of the main cap, which is adapted for ornamentation and is of relatively large size, varying as to that part thereof adapted to 15 attachment to the radiator and being uniform as to the parts thereof upon which the outer cap is arranged.

The particular object of the invention is the provision of a separate member interposed between said collar members, shown in my prior application, and adapted for simple attachment as by screw threads to the outer collar member while being movably locked upon the internal collar to prevent unscrewing of the latter from the radiator. This method of assembly is much simpler and easier for the ordinary jobber or dealer than the method of telescopic assembly of the parts, as described in my prior application 35 above referred to.

Another object of the invention is the provision of a ratchet device for causing the assembled parts to turn together in one direction for screwing the cap into place and permitting relative movement of the outer collar and sleeve with respect to the inner collar in the opposite direction to prevent the removal of the device from the radiator, or of the outer collar from said sleeve.

45 Other objects and advantages of the invention will be apparent as it is better understood from the following description, which, taken in connection with the accompanying

drawings, discloses a preferred embodiment thereof.

50 Referring to the drawings,

Figure 1 is a front elevation, partially in section, of a radiator cap in which my invention is embodied, the same being shown positioned upon an automobile radiator;

55 Fig. 2 is an elevational view, partially broken away and partially sectionalized, of the insert assembly;

Fig. 3 is a sectional view, taken substantially on the line 3—3 of Fig. 2; and

60 Fig. 4 is a section taken substantially on the line 4—4 of Fig. 2.

Fig. 5 is a partial elevational view of the radiator cap, showing the hinge connection between the cover and body.

65 The device shown on the drawings for the purposes of illustration consists primarily of an outer cap, generally indicated by the reference character 11, an inner collar 12 adapted to be secured to the radiator neck, as by screw threads 13, and a pivoted cover 14 on the cap having a motometer, or temperature indicator, 15 permanently secured thereto.

70 Upon the front of the cap is provided a projection 16, which, as shown, is of keystone form and which may receive any suitable decoration or ornamentation. The cover 14 is adapted to be held in closed position by means of a thumb screw 17, or in any other desired manner. The collar 12 is provided with circumferential grooves 18 and 19 and a sleeve 21 is provided with inwardly extending projections 22 and 23 disposed respectively within said grooves. A 75 ratchet member 24 is secured by a rivet 25 to the collar 12 and, in the present instance, is of spring material adapted to permit the projections 23 to ride thereover in one direction but to be engaged to prevent relative rotation of the sleeve in the opposite direction.

80 The sleeve 21 is provided with external threads 26 adapted to cooperate with threads 27 on the interior of an outer collar 28 which latter has laterally extending arms 29 provided with enlarged ends 31, which

preferably are of symmetrical and pleasing appearance. After the insert has been turned into the outer member 28 to the full extent, there is relatively tight frictional engagement between the threaded sleeve 21 and said outer member. An attempt to unscrew the outer member will, therefore, result in the sleeve 21 turning therewith upon the collar 12, this being readily permitted by the construction just described. When the outer member is turned in the opposite direction, the projection 23 engages the ratchet device 24, causing the collar 12 to move with the other parts whereby the device may be threaded into the radiator neck. Removal is prevented by the same means which prevents the separation of the outer member 28 and the sleeve 21, namely the connection between the sleeve 21 and the inner collar 12, which permits relative rotation of said sleeve. It will thus be impossible to remove the cap from the outside after the parts are assembled and positioned and, at the same time, the inner and outer units may be readily assembled as an incident to installing the device upon a car.

The cover 14 is provided with a rearwardly extending hinge lug 29, which is pivotally secured by means of a hinge pin 30 to an upstanding portion of the body 11, said pin being preferably arranged so that it cannot be engaged or driven out without piercing the metal of said upstanding portion of the body.

It is thought that the invention and many of its attendant advantages will be understood from the foregoing description, and it will be apparent that various changes may be made in the form, construction and arrangement of the parts, without departing from the spirit and scope of the invention, or sacrificing all of its material advantages, the form hereinbefore described being merely a preferred embodiment thereof.

45 I claim:

1. The combination of an internal collar having an opening therethrough and having means for attachment to a radiator neck, a sleeve upon said internal collar provided with screw threads, an external collar provided with screw threads adapted to cooperate with the threads on said sleeve to secure said collar upon the sleeve, a closure pivoted to said external collar and adapted to have a motometer permanently secured thereto, and means interposed between and locking said sleeve and internal collar together and permitting movement of the sleeve with the external collar to prevent removal from the radiator neck.

2. The combination of an internal collar having an opening therethrough and having means for attachment to a radiator neck, a sleeve upon said internal collar provided with screw threads, an external collar

provided with screw threads adapted to cooperate with the threads on said sleeve to secure said collar upon the sleeve, a closure pivoted to said external collar and adapted to have a motometer permanently secured thereto, and means interposed between and locking said sleeve and internal collar together, said means including a ratchet permitting relative movement of said sleeve upon said collar in one direction but not in the other.

3. The combination of an internal collar having an opening therethrough and having means for attachment to a radiator neck, a sleeve movably fitting around said internal collar when the device is assembled for use, an external collar having screw-threaded engagement with said sleeve, a pivoted closure for said external collar having an opening adapted to receive a motometer, and means enclosed between and locking together said sleeve and internal collar.

4. The combination of an internal collar having an opening therethrough and having means for attachment to a radiator neck, a sleeve fitting around said internal collar, an external collar having screw-threaded engagement with said sleeve, a pivoted closure on said external collar having an opening adapted to receive a motometer, said sleeve being locked to said internal collar but relatively movable thereon, and means preventing relative movement of the sleeve in one direction while permitting it in the other.

5. The combination of an internal collar having an opening therethrough and adapted to be screw-threaded onto a radiator neck, a sleeve movably fitting around said internal collar and locked against separation therefrom, an external collar screw-threaded upon said sleeve and adapted to have a motometer permanently secured thereto, and means for causing said sleeve to turn independently of said internal collar and with said external collar when the latter is turned in unscrewing direction.

6. The combination of an internal collar having an opening therethrough and adapted to be screw-threaded onto a radiator neck, a sleeve movably fitting around said internal collar and locked against separation therefrom, an external collar screw-threaded upon said sleeve and adapted to have a motometer permanently secured thereto, means for causing said sleeve to turn independently of said internal collar and with said external collar when the latter is turned in unscrewing direction, and means causing all said parts to turn together in direction to screw the device upon the radiator neck.

7. In a radiator cap, the combination of an outer body, an inserted attaching member, a cylindrical member upon the exterior of the inserted member and being removably attachable to the interior of said outer

body and having an inwardly projecting portion adapted to cooperate with said inserted attaching member to prevent separation of said outer body therefrom, the attaching member being inaccessible from the exterior of the cap.

8. In a radiator cap, the combination of an outer body, an inserted attaching member, a cylindrical member having a screw-

threaded connection with the interior of 10 said outer body and having an inwardly projecting portion adapted to cooperate with said inserted attaching member to prevent separation of said outer body therefrom by permitting idle rotation of the outer body, 15 the attaching member being inaccessible from the exterior of the cap.

WILLIAM V. LIPPERT.
